[57] CLAIM

[**] Term: 14 Years

The design for a hinged lunchbox, as shown and described.

[21] Appl. No.: 10,762

DESCRIPTION

[22] Filed: Jul. 19, 1993

FIG. 1 is a top, front perspective view of a hinged lunchbox showing our new design;

[52] U.S. Cl. D7/629; D9/420

FIG. 2 is a top plan view thereof;

[58] Field of Search D7/629, 709-710;
D9/414, 420, 424-425, 430; D3/273; 206/541,
545, 549

FIG. 3 is a bottom plan view thereof;

[56] References Cited

FIG. 4 is a front elevational view thereof;

U.S. PATENT DOCUMENTS

FIG. 5 is a rear elevational view thereof;

D. 135,924 7/1943 Morris .
D. 167,668 9/1952 Bendinger D9/420
D. 257,790 1/1989 Kesling .
D. 279,258 6/1985 Curtis .
D. 285,177 8/1986 Goetz D9/420

FIG. 6 is a side elevational view thereof;

FIG. 7 is a side elevational view thereof of the opposite side of FIG. 6;

FIG. 8 is a transverse cross-sectional view thereof taken

along the plane of the line 8—8 of FIG. 2; and,

FIG. 9 is a longitudinal cross-sectional view thereof taken along the plane of the line 9—9 of FIG. 2.

FIG. 1

FIG. 4

FIG. 5

FIG. 6

FIG. 7

FIG. 8

FIG. 9
